FIG. 7

INVENTOR
FRED M. YOUNG
BY ASKrob
ATTORNEY

UNITED STATES PATENT OFFICE

2,272,863

HEAT EXCHANGE TUBE PROTECTOR

Fred M. Young, Racine, Wis.

Application November 4, 1940, Serial No. 364,131

5 Claims. (Cl. 257—154)

The present invention relates to steam radiators having upper and lower headers and a number of tubes forming operating connections therebetween and a multiplicity of closely spaced fins through which the tubes extend.

Radiators of the class have an exceptionally large heat transfer surface in the fins and this type of radiator is many times smaller than the old fashioned cast radiator of the same heat transfer capacity largely because of the fact that a blast of air is forced between the fins.

The heat transfer surface in radiators of the class is quite large and therefore, during cold weather, the steam enters the header at considerable velocity. When the inlet is over or near certain tube ends, these tubes are impinged violently by the steam and they may receive a large percentage of the entering steam and thus be greatly overloaded and expanded differently from the other tubes. Furthermore, foreign matter in the steam will impinge the tube ends and the inner surface of the tubes near the ends. Thus, because of the steam velocity, foreign matter and additional heat and variations in temperature, the tubes will, in time, be injured either by abrasion, electrolysis or chemical action.

In devices of the class, it is clearly desirable to cause the many tubes in a unit to receive about the same volume of steam thus to equalize expansion and contraction and heat transfer to thereby increase the capacity of the unit.

An object of the present invention is to prevent the steam and foreign matter from violently impinging any of the tube surfaces and to evenly distribute the steam into the various tubes.

I accomplish the objects stated by providing baffles over certain tube ends which will act to receive the impact of the entering steam and foreign matter and to reduce the area of the approach to the tubes so as to equalize the flow of steam into the tubes whether they are near or a distance from the inlet.

To these and other useful ends, my invention consists of parts, combinations of parts, or their equivalents, and mode of operation, as herein-after set forth and claimed and shown in the accompanying drawing in which:

Fig. 1 is a fractional vertical section through a conventional radiator inlet header.

Fig. 2 is a top view of the device shown in Figure 1 with the top of the header removed.

Fig. 3 is a modification of the design shown in Figure 1.

Fig. 4 is a sectional view of a further modification.

Fig. 5 is a further modification of the design shown in Figure 1.

Fig. 6 is a view of the baffle shown in Figure 5 but transverse to this figure.

Fig. 7 is a modification of the design shown in Figure 3 adapted for tubes without bushings.

Fig. 8 illustrates a further modification.

As thus illustrated, in Figures 1 and 2, the top surface of the header shown is designated by reference character 10 having an inlet connection 11. The tube plate of the header is designated by reference numeral 12 and the tubes by reference numeral 13. In headers of the class, the tube ends generally extend slightly through their apertures 14, as illustrated.

A number of bushings 15 are pressed into the tube ends and expanded in any convenient manner. Most headers have the inlets in the top of the header, as illustrated. Thus it will be seen that certain tubes will be directly under the inlet and that these tubes will therefore be violently impinged by the entering steam and also greatly overloaded.

I provide baffle plates which in their entireties are designated by reference character A. These baffles comprise preferably discs 20 which are formed integrally with two or more downwardly projecting legs 21. These legs may be of any desired length, their ends being adapted to rest on tube plate 12 and thus act as spacers between the tubes and members 20. The desire is to reduce this space, if necessary, for a purpose which will be apparent.

I provide U-shaped members formed preferably integrally from strip metal into arms 22 and a connecting member 23, member 23 being preferably spot welded to member 20, the arms being positioned so they will be snugly embraced by bushings 15, the lower ends being provided with outwardly extending projections 24 which are positioned so they pass under the inner end of the bushing to firmly hold the device into position.

As thus illustrated, it will be seen that member A may be positioned a suitable distance from the ends of the tubes so as to reduce the area of the space, if necessary. The practice is to reduce the area of this space to less than the area of the tube, assuming that the pressure in the header will be slightly greater near the inlet than at the far ends of the header. Thus member A not only prevents the entering steam from impinging the tubes, but also prevents overloading these tubes.

Under some circumstances, for best results, it may be necessary to position several of the discs say $\frac{1}{8}$ " from the ends of the tubes and the surrounding discs $\frac{1}{16}$ " from the tube ends. In many installations having say 100 tubes, it may be necessary to supply baffles for six or eight tubes. In other installations, particularly if the inlet is near the end of the header of large radiators, more baffles may be needed.

In Figure 3, I illustrate a modification wherein in a disc 25 is provided with separate legs 26, their upper ends being bent outwardly at right angles as at 27 and being spot welded to the disc. An offset as at 28 is provided which rests on bushings 15 as a spacer for the discs. The lower ends of members 26 are offset outwardly as at 29, to prevent the disc from moving out of the tube by accident.

In Figure 4, I illustrate a modification wherein a tube 30 is flanged as at 31, this flange being secured to plate 25 by spot welding or otherwise. Member 30 is provided with a number of apertures 32 of a suitable size for reducing the area of the inlet to the tube. I provide an offset in tube 30 as at 33 which is adapted to rest on bushing 15. Tube 30 at its lower end is adapted to be pressed into bushings 15 so it will be firmly held into position. The lower end of the tube is flanged inwardly slightly as at 34, thus cooperating with openings 32 to reduce the opening into the tube.

In Figure 5, I illustrate a modification of the design shown in Figure 1 wherein tubes 13 are not provided with bushings but are rolled into their openings boiler tube fashion so as to provide a pressure tight joint. In this design, plate 25 is supported by a U-shaped member formed from a single strip of metal into arms 35-35 and a connecting member 36, the arms being offset inwardly as at 37-37 forming a positioning stop. The inner ends of arms 35 are curved inwardly as at 38 so as to facilitate inserting the arms into the tube.

It will be understood that the arms illustrated in Figures 1, 3 and 5 are positioned a considerable distance farther apart at their free ends than the other ends so these arms will be caused to tightly hug either the sleeve or the tube when inserted.

In Figure 6, I illustrate the design shown in Figure 5 but transverse to this figure.

In Figure 7, I illustrate a further modification somewhat similar to that shown in Figure 3, except that the disc is similar to that shown in Figure 1, the arms 40 however being made in separate pieces, the upper ends of the arms being bent at right angles as at 39 and spot welded or otherwise secured to member 20.

In Figure 8, I illustrate a baffle plate 40 large enough to cover a number of tubes or all of the tubes, as illustrated in Figure 2, and having holding means similar to that shown in Figure 5 but being spaced in pairs so the holding means will enter two of the outside oppositely positioned tubes. Clearly in this design, three holding

means may be supplied so as to fit into every other outside tube.

It will be seen that my baffle plate need not be limited to a single tube and that this plate may be formed as in Figures 1 or 7 having holding means to correspond or it may be fitted with holding means similar to that shown in Figures 3 and 4.

From the foregoing, it will be seen that many minor detail changes may be made without departing from the spirit and scope of the present invention, as recited in the appended claims.

Having thus shown and described my invention, I claim:

1. A device of the class described, comprising a radiator having upper and lower headers and a number of tubes forming operating connections therebetween, an inlet connection in said upper header, plates having holding means positioned over certain tubes which are adjacent said inlet, said holding means adapted to extend into the tubes, means adapted to determine the distance between said plates and the ends of said tubes.

2. A device of the class described, comprising a radiator having upper and lower headers and a number of tubes forming operating connections therebetween, an inlet connection in said upper header, one or more discs positioned over certain tube ends which are adjacent said inlet and having holding means adapted to extend into their tubes, legs extending from the periphery of said plates adapted to rest on the tube plate to thereby determine the distance between said disc and its tube end.

3. A device as recited in claim 2 including; said tubes having bushings therein, said holding means having relatively short projections adapted to engage the inner ends of the bushings to thereby prevent said discs from moving out of position.

4. A device of the class described, comprising a radiator having upper and lower headers and a number of tubes forming operating connections therebetween, bushings in said tube ends, an inlet connection in said upper header, one or more plates having holding means positioned over said tubes which are adjacent said inlet, said holding means adapted to extend into their tubes and be embraced by said bushings and having means to determine the distance between said plate and the ends of said tubes.

5. A device of the class described, comprising a radiator having upper and lower headers and a number of tubes forming operating connections therebetween, an inlet connection in said upper header, one or more individual plates positioned over certain tubes which are adjacent said inlet and having holding means which extend into their tubes, said tubes having inner sleeves at their ends, said holding means comprising two or more arms adapted to yieldingly engage said sleeves and having means adapted to engage the inner and outer ends of said sleeves and hold the plate into position.

FRED M. YOUNG.
